UNITED STATES PATENT OFFICE.

DAVID M. LEWIS, OF TOPEKA, KANSAS, ASSIGNOR, BY DIRECT AND MESNE ASSIGNMENTS, TO LEWIS DRAFT APPLIANCE CO., OF CHICAGO, ILLINOIS, A CORPORATION OF ILLINOIS.

APPARATUS FOR DRAFTING LOCOMOTIVES.

Application filed October 29, 1918, Serial No. 260,139. Renewed January 19, 1925.

To all whom it may concern:

Be it known that I, DAVID M. LEWIS, a citizen of the United States, residing at Topeka, in the county of Shawnee and State 5 of Kansas, have invented certain new and useful Improvements in Apparatus for Drafting Locomotives, of which the following is a specification.

My invention relates to the provision of 10 an improved means whereby the locomotive, or other form of boiler, is drafted at a low pressure, low velocity, large volume, and approximately continuous draft, in contradistinction to the standard practice of drafting.

I accomplish the foregoing and secure the 15 advantages herein set forth by means of a construction, the preferred embodiments of which I have illustrated in the accompanying drawings, wherein:

Fig. 1. is the longitudinal section through 20 the front end or smoke box of the locomotive; Fig. 2. is the section taken on the line II—II of Fig. 1; Fig. 3 is a plan view on an enlarged scale of the nozzle stand or casting; and Fig. 4 is an irregular section on 25 the line IV—IV of Fig. 3.

Referring now to the construction shown 30 in Figs. 1. and 2, the smoke box or front end is indicated by the reference letter A, such smoke box being of standard construction with the exception that it is provided 35 with a widened stack, 7, and a similarly widened petticoat, 8, the width of which is approximately equal to the width of the flue sections, 9. The major axes of the stack and petticoat are transverse of the smoke box.

An expansion chamber, B, is located 40 in front of the smoke box, in position to receive the exhaust steam from the cylinders (not shown) through the nozzle stand C the construction of which will be described. The expansion chamber discharges into the stand C, immediately above which is located the exhaust nozzle, 14, such nozzle having 45 a long narrow discharge opening, 15, the area of which is approximately equal to the area of the inlet opening, 11, by means of which the exhaust steam is lead into the expansion chamber. The area of the discharge opening in the nozzle, therefore, is greater than the area of the exhaust nozzle opening of standard designs, particularly since, in such designs, it is intended to create a high pressure, high velocity nozzle dis-

charge. The nozzle, 14, which is of approximately the same width as the expansion chamber, is provided with an annular passage, 16, cored out in its walls, and with a plurality of jets, 17, communicating therewith. Blower pressure is supplied to the chamber, 16, by means of the pipe, 18, Fig. 2 and Fig. 4, for use when desired.

The usual dry pipe, 19, and steam pipes, 20 are provided.

The nozzle stand or casting C is in the 65 general shape of an elbow, the vertical leg of which is adapted to be fastened to the saddle casting (not shown) and the horizontal leg of which extends forwardly in the lower part of the smoke box and is coupled to the 70 expansion chamber, B. The casting, C, is provided with two passages, 11^A which conduct the exhaust steam from the cylinders into the expansion chamber, B, at a point beneath the baffle or wall, 22, which extends 75 part way toward the horizontal centre line of the expansion chamber, as indicated in Fig. 2. Immediately above the passages, 11^A, the casting, C, is provided with two additional passages or channels, 11^B, which 80 communicate with the interior of the expansion chamber at a point above the baffle, 22, such channels, 11^B, expanding laterally from the front to the rear and terminating in a vertical channel or discharge opening, 11^C, 85 extending transversely of the casting. The exhaust nozzle, 14, is fitted to the casting in such a manner that its discharge outlet, 15, registers with the outlet, 11^C.

By this arrangement, I am enabled to 90 greatly increase the volumetric capacity of the expansion chamber, thus permitting the exhaust steam to expand considerably, thus reducing the back pressure, permitting low nozzle pressure and a low pressure substantially constant exhaust of low velocity but large volume, which as it enters the petticoat and stack of large volumetric capacity produces the uniform vacuum conditions throughout the smoke box and hence in the 100 flues and fire box.

The draft blast is in the form of a thin, wide column giving maximum entrainment area and it is substantially continuous in character. The effect of the expansion 105 chamber is to iron out the pulsations of the exhaust from the cylinders, such pulsations disappearing at the higher speeds.

The path of the steam is as follows:

The steam leaving the cylinders enters the lower part of the expansion chamber through the channels or passages, 11^A, then flows upwardly into the expansion chamber around the baffle, 22, filling the space thereabove, after which it enters into the passages, 11^B, into the discharge outlet 11^C, and then is discharged from the nozzle 14.

10 The casting C affords a minimum of obstruction to the smoke box and to the flow of gases therethrough and access may be had to the interior through the central opening in the expansion chamber. The location of 15 the expansion chamber exterior of the smoke box is also advantageous as it thus affords no obstruction and it can be increased to any size found necessary to produce the desired results in a given locomotive.

20 I claim:

1. In a locomotive draft appliance, the combination of an expansion chamber located exteriorly of the front end or smoke box, means for conducting exhaust steam 25 from the cylinders thereto, and means for conducting the steam therefrom to the stack.

2. In a locomotive draft appliance, the combination of an expansion chamber, located exteriorly of the front end or smoke 30 box, means for conducting exhaust steam from the cylinders thereto, and means for conducting the steam therefrom to the stack, said last means extending into the smoke box and discharging upwardly.

3. In a locomotive the combination of an expansion chamber, and a nozzle casting having a passage therethrough for conducting exhaust steam to the expansion chamber and a second passage for conducting the 40 exhaust steam from the expansion chamber to the stack, the expansion chamber having openings registering with said passages, together with means for preventing the steam discharging into the expansion chamber 45 from directly entering the second passage.

4. In a locomotive the combination of an expansion chamber having an inlet and an outlet opening, a baffle in the expansion chamber preventing direct communication 50 between said two openings, and a nozzle

casting having a passage registering with said inlet opening for conducting exhaust steam to the expansion chamber and a second passage registering with said outlet opening for conducting exhaust steam from the expansion chamber.

5. In a locomotive the combination of an expansion chamber having an inlet and an outlet opening, a baffle in the expansion chamber preventing direct communication 60 between said two openings, and a nozzle casting having a passage registering with said inlet opening for conducting exhaust steam to the expansion chamber and a second passage registering with said outlet opening for conducting exhaust steam from the expansion chamber, said second passage increasing in width and decreasing in its other dimension into a wide nozzle.

6. In a locomotive the combination of an expansion chamber located exteriorly of the smoke box, and a nozzle casting having an elbow for connection with the saddle casting and having a passage for discharging exhaust steam into the expansion chamber, 70 said passage extending substantially horizontally from the elbow to the expansion chamber, and said casting having a second passageway leading rearwardly from its forward end and terminating in a long, 80 narrow nozzle for discharging the steam from the expansion chamber, said casting being constructed at its forward end for attachment to the expansion chamber.

7. In a locomotive the combination of an expansion chamber located exteriorly of the smoke box, and a nozzle casting having an elbow for connection with the saddle casting and having a passage for discharging exhaust steam into the expansion chamber, 85 said passage extending substantially horizontally from the elbow to the expansion chamber, and said casting having a second passageway leading rearwardly from its forward end and terminating in a long, narrow 90 nozzle for discharging the steam from the expansion chamber.

In testimony whereof, I have hereunto signed my name.

D. M. LEWIS.
